UNITED STATES PATENT OFFICE.

ROBERT E. STIVERS, OF HOOPER, COLORADO.

PLUMB-LEVEL.

987,770.

Specification of Letters Patent. Patented Mar. 28, 1911.

Application filed May 20, 1910. Serial No. 562,470.

To all whom it may concern:

Be it known that I, ROBERT E. STIVERS, a citizen of the United States of America, residing at Hooper, in the county of Costilla 5 and State of Colorado, have invented new and useful Improvements in Plumb-Levels, of which the following is a specification.

This invention relates to plumb levels of that class in which a hand or pointer movable by gravity is supported adjacent to a dial divided to indicate the degrees of a circle, said hand and dial being supported by means of a suitable stock or body.

The invention has for its object to construct a device of this class which shall possess superior advantages in point of simplicity, durability and general efficiency, and in which provision is made for the convenient assemblage and adjustment of the parts.

With these and other ends in view which will readily appear as the nature of the invention is better understood, the same consists in the improved construction and novel arrangement and combination of parts which 25 will be hereinafter fully described and particularly pointed out in the claims.

In the accompanying drawing has been illustrated a simple and preferred form of the invention, it being, however, understood 30 that no limitation is necessarily made to the precise structural details therein exhibited, but that changes, alterations and modifications within the scope of the invention, may be resorted to when desired.

In the drawing,—Figure 1 is a perspective view of a device constructed in accordance with the invention. Fig. 2 is a side elevation. Fig. 3 is a transverse sectional view taken on the line 3—3 in Fig. 2. Fig. 4 is 35 a side elevation, partly in section, illustrating a slightly modified form of the invention. Fig. 5 is a top plan view, showing the modified construction. Fig. 6 is a perspective detail view of the dial and hand carrying member used in connection with the construction shown in Figs. 4 and 5.

Corresponding parts in the several figures are denoted by like characters of reference.

The stock or body A of the improved level is composed of three strips, namely, two outer strips 1, 1, and an intermediate or center strip 2, said strips being suitably connected together. The two outer strips are 55 each provided with a circular aperture 3,

and dials, such as 4, may be affixed or stamped in any suitable manner upon the portions of the faces of the center strip 2 which are visible through the side openings or apertures 3. Gravity hands or pointers 60 5 are mounted upon the ends of a stem or shaft 6 which projects through the dial portion of the center strip 2, and the side openings are protected by transparent covers 7 of glass. Apertures 8 extend from the side 65 openings 3 upwardly through the upper edges of the side strips 1, 1, forming light apertures, the same being protected by a glass cover 9.

In the modified form of the invention 70 illustrated in Figs. 4, 5 and 6 of the drawing, the top edge of the center strip 2 is provided with a recess 10 having an inverted V-shaped bottom forming a ridge 11 upon which a saddle S is adjustably supported, 75 said saddle comprising a top piece 12 having depending side members 13, each stamped or otherwise provided with a dial 14 and with an upwardly extending pin 15 upon which a gravity indicator 16 is pivotally 80 mounted. The saddle S is secured upon the center strip 2 by means of screws 16', one at each end, and it will be readily seen that by loosening one of said screws and tightening the other, adjustment of the dial-carrying saddle may be had if it shall be necessary 85 in order to true up the same. The side openings 3 and top openings 9 in the side members 1, 1 of the stock are retained, as in the construction previously described. 90

It will be seen by the construction hereinbefore set forth that I have provided a simple and efficient level, and it will be further seen that under the modified form illustrated in Figs. 4, 5 and 6 adjustment of the 95 dial members may be had. Owing to the presence of the top openings 8 the dials, although set back some distance from the outer faces of the side members of the stock, will be clearly visible, thus enabling the deflection of the indicator to be read correctly. 100

Having thus described the invention, what is claimed as new, is:—

In a level of the character described, a stock composed of a center strip and two 105 outer strips securely connected together, said outer strips being provided with circular apertures and with openings extending from said apertures to the upper faces of the strips, and said center strip being provided with a 110

recess having an inverted V-shaped bottom; a saddle supported upon the ridge thus formed and having dials, pins extending from said dials, and gravity indicators pivoted upon said pins; adjusting screws adjacent to the ends of the top member of the saddle and engaging the center strip with which the saddle is thus adjustably connect-

ed; and transparent coverings for the several openings.

In testimony whereof I affix my signature in presence of two witnesses.

ROBERT E. STIVERS.
